UNITED STATES PATENT OFFICE.

CHARLES R. BIRDSEY, OF HINSDALE, ILLINOIS, ASSIGNOR, BY MESNE ASSIGNMENTS,
TO UNITED STATES GYPSUM COMPANY, OF CHICAGO, ILLINOIS, A CORPORATION
OF ILLINOIS.

MACHINE FOR AND METHOD OF MAKING PLASTER-BOARD.

1,383,255.

Specification of Letters Patent. Patented June 28, 1921.

Application filed January 2, 1920. Serial No. 348,939.

To all whom it may concern:

Be it known that I, CHARLES R. BIRDSEY, a citizen of the United States, residing at Hinsdale, in the county of DuPage, and State 5 of Illinois, have invented certain new and useful Improvements in Machines for and Methods of Making Plaster-Board, of which the following is a description.

My invention relates to the method and to 10 that general class of devices known as machines for making plaster board or the like, and has among its objects an improved method and the production of a machine of the kind described that is simple, convenient, 15 durable, efficient, and satisfactory for use wherever found applicable, which will produce an improved board of the kind described. Many other objects and advantages 20 of the method and construction herein shown and described will be obvious to those skilled in the art from the disclosure herein given.

To this end my invention consists in the novel method, construction, arrangement and combination of parts herein shown and described, and more particularly pointed out in 25 the claims.

In the drawings, wherein like reference characters indicate like or corresponding parts,

30 Figure 1 is a longitudinal sectional view through my improved machine,

Fig. 2 is a sectional view taken substantially on line 2—2 of Fig. 1,

Fig. 3 is a sectional view taken substantially on line 3—3 of Fig. 1,

Fig. 4 is a sectional view taken substantially on line 4—4 of Fig. 1,

Fig. 5 is a sectional view taken substantially on line 5—5 of Fig. 1,

40 Fig. 6 is a perspective view of a portion of the board manufactured on the machine, and in accordance with method, and

Fig. 7 is a sectional view of a portion of a similar board showing a slightly different 45 arrangement of the parts.

Referring to the drawings, it may be mentioned that the type of board which this machine is adapted to construct is illustrated in my pending application Serial Number 50 247,244, filed July 29, 1918. As shown in Fig. 1, 1 represents a suitable conveyer of a fixed or movable type, as shown, an endless conveyer which may extend over pulleys similar to 2, or the equivalent, carried on the

frame 3. A sheet 4 of paper or other suitable 55 material is fed onto the conveyer from a supply roll 5, the same, however, preferably passing under the scoring wheels 6 or the equivalent arranged to score the sheet 4 at the points where the same is to be folded. As 60 shown, the sheet 4 extends over and is supported by the conveyer 1, suitable provision being made for discharging stucco, plaster, or other plastic material 9 on the same.

As shown, a conveyer 10 is provided, the 65 same receiving the stucco and discharging it in a plastic state onto the sheet 4. I have not considered it necessary to illustrate herein the conveyer 10 in detail, nor the preparation of the plastic material, as this forms no part 70 of the present invention, but it may be said, however, that the stucco or the equivalent, and other ingredients, if desired, may be mixed on the conveyer or its equivalent in any suitable manner with water or the like 75 and thence discharged onto the sheet 4.

At each side of the table, adjacent the conveyer 1, is a member 8, the same being arranged to engage the edges 4' of the sheet and fold or turn the same up at the scoring marks 80 and maintain the same in the turned up position. I provide rolls 11 and 12 preferably arranged as shown. The upper roll 12 is arranged between the side bars 8, the construction of the parts being such, however, that 85 there is a space 17 between the end of the roll and the inner side of the edge 4' of the sheet, so that some of the material may flow upon the side of the sheet. A cover sheet 15, of paper or the equivalent, from a supply roll 90 16 is passed over and under the roll 12, as shown, and forms one of the covering sheets of the finished board.

After the sheet 15 is applied on the stucco, the edges 4' of the sheet 4 are folded in or 95 turned over and upon the same. For this purpose I show turning members 17 which engage the upturned edges 4 and fold or turn them over and down as indicated in Fig. 4. These folding members are arranged in advance of the rolls 18 and 19, which rolls are preferably so arranged as to even and gage the thickness of the board so as to produce a uniform product. They are generally set so that the edges 4' are 100 depressed flush with the face of the board. After passing the rolls 18 and 19, the same may be passed between the edge-smoothing

rolls 20, which are shown provided with a flange 21 overlying the board and with a driving shaft 22.

It will be noted by referring to Fig. 3, 5 that as the board is passed between the rolls 11 and 12, a portion of the material may be squeezed out into the space between the ends of the roll and the inner side of the upturned edge of paper or covering sheet. This provides 10 a seal for the turned over sheet, as will be seen by referring to Fig. 6, in which the portion of the material between the end 15' of one cover sheet and the edge 4' of the other cover sheet seals the two sheets together.

It will be seen that after scoring the board cover sheet I hold up the edges of the sheet and apply the stucco, then apply the second cover sheet and press the same in the first 20 sheet so as to properly set the same in place and then I apply or cause a portion of stucco to flow upon the upturned edges and then turn the edges down on the top sheet and press them into place.

25 In Fig. 7 the cover sheet 24 is shown turned over as at 25 over the top sheet 26, the edge of which 27 extends as shown. In this case the material 28 between the edges 27 and 25 seals the same. In this particular illustration the edge 27 is substantially parallel with the edge 25 instead of slightly inclined as shown in Fig. 6. The appearance of the resulting product, however, from the exterior is substantially the same, and the 30 utility is the same. I wish it to be understood that while both edges are preferably folded over or inclosed the board may be constructed with only one edge so inclosed.

Having thus described my invention, it is 40 obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure 45 by Letters Patent is:

50 1. In a machine of the kind described and in combination, a conveyer, means for supplying the cover sheet of suitable material thereto, means for folding up the edges of the sheet and maintaining the same turned up, means for depositing a plastic body on the sheet between said turned up edges, means for applying a second cover sheet on said plastic body, means for folding said edges of the first sheet over onto the second 55 cover sheet, and means for pressing the same down on the said second sheet.

2. In a machine of the kind described and in combination, a conveyer, means for supplying a sheet of covering material thereto, 60 means for scoring said sheets adjacent the

opposite edges, means for turning the edges up, means for depositing a plastic body on the sheet, means for applying a second cover sheet over said plastic body and between the edges of the first sheet, means for thereafter turning said upturned edges in over the second cover sheet, and means for pressing the same down on the sheet. 70

3. In a machine of the kind described and in combination, a movable conveyer, means for supplying a sheet of covering material thereto, means for scoring said sheets at a plurality of points adjacent the opposite edges, means for turning the edges up, means for depositing a suitable plastic body 80 on a sheet, means for applying a second cover sheet over said plastic body and between the upturned edges of the first sheet, means for thereafter folding said upturned edges inwardly over the second cover sheet, 85 means for pressing the same down on the sheet, and means for straightening the edges.

4. In a machine of the kind described and in combination, means for supplying a cover 90 sheet of suitable material thereto, means for scoring said sheet adjacent the opposite edges, means for folding up the edges, means for depositing a plastic body on the sheet, a roll arranged above said sheet and spaced therefrom, said roll extending between said folded edges, but of a length whereby the ends of the roll are spaced from the said folded edges, means for feeding a second cover sheet extended over said roll, means 95 for folding down said edges, after said sheets and plastic material body have passed said roll and a second roll arranged to press said folded over edges down on the second sheet whereby a portion of the plastic material is 100 forced over the edges of the second cover sheet and between the sheet and said folded over edges and the sheets secured together.

5. In a machine of the kind described and in combination, means for supplying a cover 110 sheet of suitable material thereto, means for folding up the edges, means for depositing a plastic body on the sheet, a roll arranged above said sheet and spaced therefrom, said roll extending between said edges, but of a length whereby the ends of the roll are spaced from the said upturned edges a distance sufficient to permit the plastic material to flow up the edges, means for feeding a second cover sheet extended over said roll, 115 means for folding down said edges after said sheets and plastic material body have passed said rolls and a second roll arranged to press said folded over edges down on the second sheet whereby a portion of the plastic material 120 on the edges is forced over the face of the second cover sheet between the sheet and said folded over edges. 125

6. A method of constructing plaster board consisting in providing a cover sheet and 130

5 folding up the edges of the cover sheet and applying a plastic material thereon between the upturned edges, thence applying a top cover sheet and pressing the same down on the plastic material, thence folding the said edges of the first sheet down on the second cover sheet, and pressing the edges down to the said sheet and secure the same together.

7. A method of constructing plaster board 10 consisting in folding up the edges of a cover sheet and applying a plastic material thereon between the upturned edges, thence applying a top cover sheet and pressing the same down on the plastic material, providing a surplus of material at said upturned edges, thence folding the upturned edges down on the face of the second cover sheet and said surplus material, and pressing the edges down on the surplus material and the 15 said second sheet whereby the two sheets are substantially secured together by the surplus material between the two.

8. A method of constructing plaster board 20 consisting in folding up the edges of a cover sheet and applying a plastic material thereon between the upturned edges, thence applying a top cover sheet on said plastic material and pressing the same on the plastic material causing the surplus material to flow

out at the edges of the second cover sheet, 30 thence folding in the upturned edges of the first mentioned sheet over on the second mentioned cover sheet and pressing the same down on the second sheet whereby the surplus material flows between the two sheets 35 and substantially seals the same.

9. A method of constructing plaster board 40 consisting in folding up the edges of a cover sheet and applying a plastic material thereon between the upturned edges, thence applying a top cover sheet on the same and pressing the same on the plastic material causing a portion of the plastic material to flow out over the edges of and onto the second cover sheet, thence folding the upturned 45 edges of the first mentioned sheet down on the second mentioned cover sheet and pressing the same down on the second sheet whereby the surplus material between the two sheets substantially secures the same together. 50

In testimony whereof, I have hereunto signed my name in the presence of two subscribing witnesses.

CHARLES R. BIRDSEY.
